UNITED STATES PATENT OFFICE.

SVEND E. JOHANNESEN, OF PITTSFIELD, MASSACHUSETTS, ASSIGNOR TO GENERAL ELECTRIC COMPANY, A CORPORATION OF NEW YORK.

COIL AND SPOOL CONSTRUCTION.

Application filed February 6, 1920. Serial No. 356,583.

To all whom it may concern:

Be it known that I, SVEND E. JOHANNESEN, a citizen of the United States, residing at Pittsfield, county of Berkshire, State 5 of Massachusetts, have invented certain new and useful Improvements in Coil and Spool Constructions, of which the following is a specification.

My invention relates to a coil and spool 10 construction, and more particularly to the instrumentalities used for forming the coil upon its spool.

One object of my invention is to form the coil expeditiously upon its spool, and in such 15 a manner that the minimum space be utilized for the coil. Another object is to provide means for preventing the end turn of any layer from slipping down onto the next lower layer. Still another object is to use 20 such a form of conductor that two electrically independent coils, such as two secondaries on a transformer, may be expeditiously wound in one operation. Other objects and 25 advantages of my invention will appear as the description proceeds.

In general, my invention comprises the employment of a spool of a definite configuration, for properly guiding the turns of wire. It is to be understood that this 30 spool may be used both in the case where the turns of wire are placed on the coil by hand, as well as by machines. The most efficient form of winding, as far as space is concerned, is the so-called gutter winding, or 35 one in which each succeeding layer of turns is wound in the gutter formed by the turns in the next lower layer. Difficulty, however, is usually experienced in preventing the end turn of the layer from dropping down, due 40 to the fact that it is offset by one-half the diameter of the conductor from being directly over the bottom turn. I provide means, such as small hemispherical projections upon the spool, for furnishing a support for this end turn at the proper point. I further provide means for definitely determining the place of cross-over of each turn 45 on the bottom layer.

The construction and operation of my invention may be readily understood by reference to the accompanying drawings, in which:

Figure 1 is a perspective view showing the

spool that I employ for winding the coil; Fig. 2 is a longitudinal sectional view of the 55 completed coil; Fig. 3 is a view of the coil showing the first completed layer of turns; Fig. 4 is a view of the coil showing the second layer of turns completed, and Fig. 5 is a cross-sectional view similar to Fig. 2 showing a modification.

Referring now more in detail to the drawings, wherein like reference numerals refer to like parts throughout, the spool 11 has the ordinary conventional flanges 12 at each end 65 thereof. This spool may be used only while the coil is being wound for forming it, or may be incorporated as a part of the coil. The manner in which the spool is wound is shown clearly in Figs. 3 and 4. The first 70 layer is started at 13, Fig. 3, and each turn thereof crosses over to the next turn at the point marked 14. In this way, each turn makes practically a complete circle all in one plane, instead of describing a helix. Such 75 a helical coil, however, could be used with my invention, as well as the kind I illustrate. In order to determine the point 14 where the cross-over is to take place for the first layer of turns, I make use of some means, such 80 as a diagonally extending narrow ridge 15. This ridge has the desired effect of facilitating the cross-over at that point. It is only in the first layer that a special guide such as a ridge for forming a definite cross-over 85 is needed; in succeeding layers the turns are kept from being wound in a helix by winding them in the gutters of the lower layer. These gutters form a sufficiently good guide for this purpose.

Each successive turn on the bottom layer is now placed on in exactly the same way. The distance between flanges 12 is such that one-half space is left as indicated by dimension "A" on Fig. 3. To prevent the last 95 turn from spreading, and also to support the next layer of turns, means are provided, such for example as the hemispherical projection or knob 16, projecting from the flange 12 a distance equal to the radius of the 100 overall dimension of the wire used. This knob is appropriately positioned, as shown, for the proper fulfillment of its function. The last turn "B" at the right-hand side of Fig. 3, however, comes up from under the 105 spool as the last turn "C" at the left-hand

side, then rises gradually and forms the beginning "D" of the second layer. Attention is called to Fig. 2, showing how the projection 16 supports this first turn of the second layer and prevents it from slipping down.

The second layer of turns is now placed on in the manner clearly shown in Fig. 4. The manipulation of the last turn of this layer is precisely the same as the last turn of the first layer. In this case the projection 17 is made use of in the same way as projection 16. Each succeeding layer is then placed on, and other projections, such as 18, 19 and 20, are utilized for these layers in the same way as projections 16 and 17. Apertures 21 and 22 are provided for the leading-in wires of the coil.

In Fig. 5 I have shown my invention as applied to a transformer winding or the like, wherein more than one electrically independent coils are wound on one spool. In order to be able to use the improvements I have described above efficiently with such a coil, both conductors are wound simultaneously, although electrically independent. The two conductors 23 are approximately semi-circular in cross section and are separated by flat insulation 24. Both conductors are covered, for example, by the insulation 25, which thus serves the double purpose of insulating the turns from each other and also to unite mechanically the two independent conductors. Thus the two coils may be wound on the spool in one operation.

In both of the forms illustrated, the need of a larger support for the end turns than the projections 16, 17, etc., is obviated by locating these projections where the end turn begins.

While I have shown in the accompanying drawings the preferred embodiments of my device, my invention is not limited thereto, and I aim in the appended claims to embrace all modifications falling fairly within the scope of my invention.

What I claim as new and desire to secure by Letters Patent of the United States, is,—

1. In a spool, a spool body adapted to be wound with turns of wire, flanges thereon, and projections carried on those surfaces of said flanges which are adjacent the turns of wire for supporting the end turns of each layer.

2. In a spool, a spool body adapted to be wound with turns of wire, flanges thereon, and a diagonal ridge on the outer surface of said spool body, running from one flange to another, to determine the cross-over point of

each succeeding turn on the first layer of the winding.

3. In a spool, a spool body adapted to be wound with turns of wire, flanges thereon, means comprising projections carried by the flanges for supporting the end turns of each layer, and a diagonal ridge on said spool body for determining the cross-over point of each succeeding turn on the first layer of the winding.

4. In a spool, a spool body adapted to be wound with turns of wire, flanges thereon, hemispherical projections carried by the flange surfaces for supporting the end turns, said projections having a diameter equal to that of the wire which is to be wound upon said spool, and so arranged that there is one projection for each layer of the winding, and located on opposite flanges for the alternate layers.

5. In a coil, a spool body, a compound conductor of circular shape formed of two electrically independent conductors mechanically united wound thereon, flanges for said spool body, and projections carried on those surfaces of said flanges which are adjacent the turns of wire, for supporting the end turns.

6. The combination with a gutter wound coil of a flanged member for supporting the same, provided with projections on those surfaces of the flanges which are adjacent the turns of wire, for supporting the end turns of each layer.

7. The combination with a gutter wound coil of a spool for supporting the same, said spool having a diagonal ridge on the outer surface of its body running from one flange to another, to determine the cross-over point of each succeeding turn on the first layer of the winding.

8. The combination with a gutter wound coil of a flanged member for supporting the same provided with projections alternately disposed on the respective flanges and positioned to engage the outside of the last turn of each layer to prevent it from spreading, the distance between the flanges being such that a space equal to substantially one-half the diameter of the wire is left between the last turn in each layer and the adjacent flange, the respective projections filling these spaces at a point in the winding.

In witness whereof, I have hereunto set my hand this the third (3rd) day of February, 1920.

SVEND E. JOHANNESEN.
